SECTIONAL FORMING ROLL FOR TUBE MILLS
Lewis H. Ruple, Perrysburg, Ohio, assignor to Abbey
Etna Machine Company, Perrysburg, Ohio, a corpora-
tion of Ohio

Filed Jan. 10, 1961, Ser. No. 81,783
1 Claim. (Cl. 153—54)

This invention relates to tube mills in which a long flat strip or ribbon of sheet metal is gradually formed into tube form and then the edges are welded together. More particularly, however, this invention is concerned with the sectional forming rolls and an object is to improve the structure of the sectional forming rolls for rendering them more efficient, sturdier, more rugged, and capable of effectively withstanding the thrusts imposed thereon, and facilitate the assembly.

Other objects and advantages of the invention will hereinafter appear and for purposes of illustration but not of limitation, an embodiment of the invention is shown on the accompanying drawings in which

FIGURE 1 is a side elevation of stand containing driving and forming rolls of a tube mill;

FIGURE 2 is an enlarged view of the sectional forming roll, parts being broken away to show in section the structure of the roll parts;

FIGURE 3 is a transverse sectional view substantially on the line 3—3 of FIGURE 2; and

FIGURE 4 is an enlarged sectional view of one of the flange sections of the forming roll.

The illustrated embodiment of the invention comprises a supporting base or bed 10 on which is mounted an upright stand containing a pair of driving and forming rolls, the stand consisting of a pair of upright laterally spaced pedestals 11 and 12, bolted firmly to the bed 10. Disposed between and carried by the pedestals 11 and 12 is an upper feed roll 14 which has a transversely curved peripheral surface, the roll being fixed for rotation to a transverse spindle 15 which is suitably mounted in bearings in the pedestals 11 and 12. A tie rod 13 provides an operative connection with adjusting screws which enable the spindle 15 to be adjusted vertically from a single point on the front pedestal 12. At one end of the spindle is disposed a universal joint 16 to which is connected a driving shaft 17 for positively rotating the roll 14.

Disposed below the roll 14 is a lower feed and forming roll, generally indicated at 18, which is mounted on a spindle 19 rotatable at its ends in suitable bearings in the pedestals 11 and 12. The roll 18 is similarly provided with a universal joint 20 and has a driving shaft 21.

The lower forming and feed roll 18 is made up of three separate sections. It has a central driving section 22 and a pair of independently rotatable flange sections 23 and 24 arranged respectively at opposite ends of the central section 22. The central section 22 is connected to the spindle 19 by a key 25 and the exterior of the section 22 conforms to the curvature of the upper roll 14 so that a ribbon or strip of sheet metal between these two rolls is clamping engaged by the driven central section 22 and the upper roll 14 for feeding the strip or ribbon forwardly as well as to assist in the shaping of the strip. The upper roll 14 and the driving section 22 are driven at mating peripheral speeds by the respective drive shafts 17 and 21.

The flange sections 23 and 24 are similar to each other except the curvature on one side of course is in one direction and the other is in the opposite direction, so that detail description of one of the flange sections is deemed sufficient. It will be noted that the exterior of each flange section has an upward and outward curvature but this curvature varies in accordance with the particular location of the stand because as the strip advances, the curva-

2

ture becomes more abrupt to effect the coiling of the strip into tube form. Each flange section is mounted on an elongate sleeve 26 which in turn is keyed to the spindle 19. As shown, a key 27 is interposed between the spindle and the sleeve.

At the inner end of the sleeve 26 is an annular collar 28 which provides an abutment against which one of the races of a roller thrust bearing unit 29 abuts, the other race abutting against a shoulder 28a formed by an annular recess in the adjacent flange section. Spaced axially from the roller thrust bearing unit 29 is a similar thrust bearing unit 30. Abutting against the outer end of the sleeve 26 is a ring 31 which is secured to the sleeve 26 by a series of bolts 32. The ring 31 has an annular lip 33 which abuts against the inner cage of the thrust bearing unit 30, the outer cage abutting against a shoulder 33a formed by an annular recess in the flange section. Fitting between the outer end of the ring 31 and the shoulder 35 on the spindle 19 is a thrust sleeve 34 which fits over the spindle and transmits the thrust from the flange section parts to the shoulder 35.

Abutting against the outside of the flange section is an annular plate 36 which is secured to the flange section by a series of bolts 37. The plate 36 has a boss-like projection 36a which fits the edge portion of the flange section. The flange plate 36 cooperates with the ring 31 to provide an annular space to receive a lubricant seal assembly 39 of well known construction. A similar lubricant seal assembly 38 fits the annular collar 28 and cooperates with a ring 38a which is pressed into a socket formed in the inner end of the flange section. Thus the lubricant seals 38 and 39 seal the opposite ends of the cavity formed between the sleeve 26 and the flange section, this space receiving the roller thrust bearings 29 and 30 and providing a lubricant reservoir 40 which can be filled with lubricant from a diagonal passage 41 which leads to the outside and is closed by a screw plug 42.

It will be understood that various sets of feeding and forming rolls 14 and 18 are of different cross sectional shapes successively to bend the strip of metal gradually to the desired form. It is important that the maximum diameter of the upper forming roll 14 and the minimum diameter of the center section 22 of the lower roll 18 travel at the same peripheral speed for the reason that these middle members constitute the driving elements for effecting travel of the strip through the machine without effecting a bending or curling thereof longitudinally.

By employing one pair of feed rolls in each set in association with two idle flange sections, the latter are driven entirely by contact with the metal strip and may rotate at such relative speeds as the strip itself effects by the speed of travel through the machine. In this way there is no strain or stress placed upon the metal strip, such as would result from the use of driving elements in the place of the idle flange sections when providing accurate means for rotating the opposed pairs of forming rolls at exactly the right proportionate speeds. The strips consequently leave the machine without being curled or distorted to any appreciable extent and the metal is not scored.

The advantages of the above described forming roll 18 are multifold both from the aspect of operation as well as assembly. In the first place, the center section 22 is fixed to the driving spindle so that it maintains a constant relation with and rotates in conformity to the upper roll 14. By mounting the end flanges 23 and 24 on roller thrust bearings, these flange sections rotate freely regardless of the degree of thrust imposed thereon. It will be recognized that these parts are extremely heavy, some assemblies weighing over a thousand pounds, and, unless the flange sections can rotate freely under enormous lateral thrust conditions, the metal ribbon will become scored and

as a result the finished tube will be downgraded. By disposing the roller thrust bearings in a bath of lubricant which can from time to time be replenished, the parts at all times run substantially free of friction. The lubricant is effectively sealed within a chamber by sealing units at opposite ends thereof.

The number of parts is reduced to a minimum and the ease of assembly is manifest from inspection of the drawings. With the front pedestal 12 removed and the roll spindles 15 and 19 supported by the rear pedestal 11, the first inner flange section 24 is mounted followed by the center section 22, the upper roll 14 and then the outer flange section 23. The flange sections are simple in design so as to facilitate machining operations and keep the cost as low as possible.

Numerous changes in construction and arrangement may be made without departing from the spirit of the invention, especially as defined in the appended claim.

What I claim is:

In a tube mill having sets of cooperative feed and forming rolls for progressively shaping a ribbon of sheet metal into tubular form and advancing same and in which one of the rolls of each set has a central driven feed section and independently rotatable end flange sections mounted on a driven shaft, the improvement which comprises an elongate sleeve for each flange section concentrically mounted on the drive shaft at opposite ends of the central driven feed section, a pair of axially spaced roller

thrust bearings interposed between each of said sleeves and the respective flange section for affording free rotation thereof regardless of the thrust load imposed thereon, each sleeve and its respective flange section defining therebetween a lubricant cavity communicating with both of said thrust bearings, lubricant seal means between each sleeve and the respective flange section at inner and outer opposite ends of said cavity at the outer sides of said thrust bearings for closing the ends of said cavity, a pressed-on member for retaining the inner of each lubricant seal means in place, a pair of spaced concentric plates bolted to each flange section and sleeve respectively and receiving the outer lubricant seal means therebetween, and conduit means for introducing lubricant to said cavity from the exterior of the respective flange sections.
